UNITED STATES PATENT OFFICE.

JOHN JOSEPH SLEPICKA, OF NEW CASTLE, PENNSYLVANIA.

SLED.

Application filed July 1, 1921. Serial No. 481,908.

To all whom it may concern:

Be it known that I, JOHN J. SLEPICKA, a citizen of the United States, residing at New Castle, in the county of Lawrence and State of Pennsylvania, have invented a new and useful Sled, of which the following is a specification.

This invention relates to sleds, one of its objects being to provide a structure of this character having means whereby shocks will be absorbed, thereby to protect the occupant from severe jolts and the like due to traveling over rough surfaces.

A further object is to provide improved means whereby the sled can be steered readily.

Another object is to provide a sled which is durable in construction and of neat appearance.

20 With the foregoing and other objects in view which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings the preferred form of the invention has been shown

In said drawings

Figure 1 is a plan view of the sled.

Figure 2 is a side elevation thereof.

35 Figure 3 is a transverse section through one of the shock absorbers and adjacent parts.

Figure 4 is an enlarged section on line 4-4, Figure 3.

40 Figure 5 is a rear elevation.

Figure 6 is a plan view of the steering head.

Referring to the figures by characters of reference 1 designates runners preferably 45 formed of T-strips the forward ends of which are upturned as shown at 2. On these runners are mounted substantially U-shaped bolsters or supports 3 provided with inclined braces 4. The bolsters are 50 connected at their sides by longitudinal strips 6 and these in turn are reenforced by braces 7 connected to the strips and to the runners. Each of the bolsters is preferably channeled longitudinally as shown at 8, thus 55 to provide a longitudinal reenforcing rib 9.

Mounted on each bolster adjacent each

side thereof is a yoke 10 which straddles the bolster and is movable vertically relative thereto. Each yoke also straddles a cushion 11 preferably of rubber which rests on the 60 bolster and the various parts serve to support a board 12 constituting the body of the sled. This board, the yoke 10, the cushions 11, and the bolster are held assembled by a bolt 13 extending therethrough and engaged 65 by a retaining nut 14. This bolt is slideable within an opening 15 formed in the bolster. Thus it will be seen that the support 12 is free to move slightly relative to the bolster, the rubber cushions or springs 11 serving 70 to absorb shocks and the yokes 10 constituting means for holding the board against longitudinal shifting relative to the bolsters. In other words these yokes constitute guides which allow the board 12 to move vertically 75 to a limited extent relative to the bolsters but prevent said board from shifting backwardly or forwardly.

Secured to and extending forwardly of the center of the board 12 is a flat metal 80 loop 16 in which is mounted a steering bar 17 having terminal grips or handles 18. This bar is pivotally attached to the loop at its center, as shown at 19. A T-shaped plate or steering head 20 is arranged under 85 the loop and is mounted on the pivot 19, the laterally extending wings 21 of this steering plate being fastened to the bar 17 while the forwardly extending arm or tongue 22 of the plate is connected to the front end portions 90 of the runners by means of links 23.

It is to be understood that the runners are flexible to a limited extent and, therefore, when the bar 17 is swung about its pivot the plate 20 will be moved therewith 95 so as to cause the tongue 22 to swing to the right or to the left. Consequently the tongue will thrust or pull through the links 23 upon the respective forward portions of the runners so as to flex the runners 100 laterally.

For the purpose of reenforcing the sled longitudinally a side strip or brace 24 can be secured at its rear end to the top of the rear bolster 3 and at its forward end to the 105 loop 16, as shown in Figure 2.

What is claimed is:

In a sled the combination with runners and bolsters secured thereon, of a body, rubber springs interposed between the body 110 and bolsters, bolts connecting the body and bolsters and extending through the springs

22
to permit up and down movement of the body relative to the bolsters, and yokes secured to the body by said bolts and straddling the rubber springs and the bolsters to hold the body against longitudinal movement relative to the bolsters and to relieve the bolts of transverse strain.

In testimony that I claim the foregoing as my own, I have hereto affixed my signature in the presence of two witnesses.

JOHN JOSEPH SLEPICKA.

Witnesses:

ELIZABETH HARTSUFF,

CLARE M. HARTSUFF.
